CLAIM

The new ornamental design of a tool case apparatus, as shown and described.

DESCRIPTION

FIG. 1 is a perspective view, depicting a tool case apparatus of the present invention;

FIG. 2 is a side view, depicting the tool case apparatus of FIG. 1;

FIG. 3 is a top view, depicting the tool case apparatus of FIG. 1;

FIG. 4 is a front view, depicting the tool case apparatus of FIG. 1;

FIG. 5 is a back view, depicting the tool case apparatus of FIG. 1; and,

FIG. 6 is a bottom view, depicting the tool case apparatus of FIG. 1.
